(57) **CLAIM**

The ornamental design for a watch, as shown and described.

DESCRIPTION

FIG. 1 is a perspective view of a watch in accordance with my invention thereof;

FIG. 2 is a top view thereof;

FIG. 3 is a right side view thereof;

FIG. 4 is a bottom view thereof;

FIG. 5 is a left side view thereof; and,

FIG. 6 is a front view; rear view is mirror image thereof.

The broken lines shown in FIGS. 1 and 2 are for illustrative purposes only and form no part of the claimed design.

1 Claim, 4 Drawing Sheets**FIG. 1**

FIG. 2**FIG. 6**

FIG. 3

FIG. 5

FIG. 4
